FRED L. EBERHARDT AND HENRY F. EMME, OF NEWARK, NEW JERSEY,
ASSIGNORS TO GOULD & EBERHARDT, OF NEWARK, NEW JERSEY, A
CORPORATION OF NEW JERSEY.

GEAR-CUTTING ENGINE.

SPECIFICATION forming part of Letters Patent No. 700,184, dated May 20, 1902.

Application filed May 8, 1901. Serial No. 59,194. (No model.)

To all whom it may concern:

Be it known that we, FRED L. EBERHARDT, residing at 17 Hillside avenue, and HENRY F. EMME, residing at 896 South Seventeenth street, Newark, Essex county, New Jersey, citizens of the United States, have invented certain new and useful Improvements in Gear-Cutting Engines, fully described and represented in the following specification and the accompanying drawings, forming a part of the same.

The present invention relates to that class of automatic gear-cutting machines in which a single driving-shaft is connected by various trains of gearing with the worm and worm-wheel for shifting the blank, with the cutter for cutting the blank, and with the feeding devices which reciprocate the cutter-head upon the cutter-slide.

The present improvements relate especially to that class of gear-cutters in which vertical and horizontal inclinations of the cutter-slide are required for cutting bevel-gears and worm-gears.

The primary object of the invention is to operate the machine by a single driving-shaft upon the machine itself and in permanent connection with the different trains of gearing, so that the various adjustments and movements of the parts are effected without varying the relation of the driving-shaft itself. To effect this result, the driving-shaft is mounted in a bearing on a line with the joint of the hinge-plate, which adjusts the cutter-slide at vertical angles, and the driving-shaft thus maintains a uniform relation with the cutter-slide whatever the position of the latter. In machines for cutting worm-wheels the cutter-slide is pivoted upon the hinge-plate, so

as to be set at various horizontal angles, and to connect the driving-shaft with such an adjustable cutter-slide a universal joint is inserted in the train of gearing which connects the driving-shaft with the feed-gearing upon the cutter-slide. Where the hinge-plate is supported upon an adjustable table, the bearing for the driving-shaft is attached to such table, so as to maintain a fixed relation with the pivot of the joint of the hinge-plate what-

ever the adjustment of the table. Such an arrangement of the driving-shaft permits a single pulley to be used for driving the entire machine and permits a single belt to operate the machine in all its various adjustments without any variation in its tension. 50

Another object of the invention is to vary the speed at which the blank or the cutter may be rotated without modifying the speed of the driving-shaft. This is effected in the case of the cutter by connecting the driving-shaft with the cutter by a train of gearing in which change-wheels are inserted to change the speed of the cutter as required. In the case of the dividing mechanism which shifts the blank the driving-shaft is connected with the shifting-worm by a train of gearing in which change-wheels are also inserted to effect the object, and the worm can be thus rotated more rapidly in cutting small pinions, so as to save time in shifting the 70 blank through a large arc. Such change-wheels perform an entirely different function from those connected with the worm and with the stop mechanism which determines the arc of rotation. 75

The invention also includes an adjustable brace for the outer end of the mandrel.

The invention will be understood by reference to the annexed drawings, in which—

Figure 1 is a side elevation of a gear-cutter 80 provided with our improvements and the cutter-slide in a horizontal position to cut the cylindrical blank shown upon the mandrel. Fig. 2 shows an elevation of the cutter-slide in an inclined position. Fig. 3 is a plan of the machine, and Fig. 4 is a rear elevation. Figs. 5 and 6 show a support for the mandrel o.

The bed a is shown with column b, upon which the mandrel o is supported in bearing o', and the blank q is rotated by worm-wheel 90 r, which is indicated by dotted lines in Fig. 4 and is concealed by a casing r' in Fig. 1. A table c is adjustable upon the bed in the usual manner by means of the screw b', which is shown only in Fig. 1, and the hinge-plate d is hinged to the table at the rear end by joint e. The hinge-plate is provided with segments f and the table with a shaft and

- gears f' to elevate the hinge-plate as desired. The cutter-slide h is pivoted upon the hinge-plate by stud h^2 , (see Fig. 3,) and the slide and the hinge-plate are connected by slots 5 and bolts h' to provide for horizontal angular adjustment of the slide. The driving-shaft e' is mounted in a line with the joint e in a bearing g , attached to the table c , which is provided, as shown in Fig. 4, with a downwardly-projecting flange for such purpose. A driving-pulley P is shown upon the shaft e' , and this pulley, which may be driven by a single belt, serves to operate all the mechanism of the entire machine. The segments f are attached to the hinge-plate concentric with the said joint and bearing, but are fixed to the hinge-plate at one side of such bearing, as shown in Fig. 2.
- The cutter-head i , carrying the cutter-spinning j , is mounted upon the cutter-slide and shown with feed-screw k extended into a gear-case k' upon the forward end of the cutter-slide. Such case is commonly used to contain the reversing-gearing to turn the screw 25 in opposite directions to reciprocate the cutter-head; but such gearing forms no part of the present invention and may be made of any usual character. A gear k^2 , which is usually formed with a threaded hub, is shown 30 upon the forward end of the screw, and a gear k^3 is shown below the box in Fig. 1, which would in practice be connected with the gear k^2 by a reversing-clutch to be operated in the usual manner.
- 35 A shaft l is connected with the driving-shaft by bevel-wheels p' and is extended to the gear-case k' , being supported in a bearing d' upon the hinge-plate and a bearing h^3 upon the gear-case and provided near its ends 40 with universal joints l' , which preserve the connection of the driving-shaft with the gear k^3 when the cutter-slide is adjusted horizontally. The shaft l connects one of the universal joints with the other through a splined 45 sleeve l^2 , which slides upon the shaft as required in its various adjustments. The horizontal adjustment of the cutter-slide operates to bend the shaft l , and thus necessitates the provision of the universal joints l' and of the 50 splined sleeve l^2 to permit a slight longitudinal play of the shaft l between the two universal joints.
- The cutter c' (shown in Fig. 3) is connected with the driving-shaft by change-wheels m 55 and shaft m' , which is extended from the gear-case k' , through the bevel-wheels s , which drive the change-wheels m , the shaft being splined to slip through one of the bevel-wheels as the cutter-head reciprocates upon the slide.
- 60 Gears n' are shown behind the change-wheels to normally reduce the speed of the cutter, and the change-wheels m are shown of equal diameter, but may be removed and others of various proportions substituted to vary the 65 speed of the cutter. The head of a screw b' is shown in Fig. 1 for moving the table upon

the bed to and from the column, as is usual, and all of the gearing heretofore described is moved with such table, and the relation of all the parts is thus preserved. 70

The coincidence of the driving-shaft e' with the joint of the hinge-plate preserves the relation of the shaft l with the driving-shaft in all positions of the cutter-slide, as is clearly indicated in the inclined position of the slide 75 shown in Fig. 2.

The train of gearing connecting the driving-shaft e' with the dividing-worm n comprises a horizontal shaft t and upright shaft t' , which are connected by the change-wheels t^2 and by the usual friction-driver t^3 . The bracket carrying the bearing g is provided also with bearings g' and g^2 and with bevel-wheels a' , through one of which the shaft t is fitted to slide with a spline to compensate for 85 various adjustments of the table c . The change-wheels t^2 are shown in Figs. 3 and 4 of different diameters adapted to reduce the speed of the worm n below that of the driving-shaft; but the change-wheels may be removed and others substituted to drive the worm at the same speed or at a greater speed than the driving-shaft. The shaft t' is also provided with a spline, as shown at t^4 in Fig. 4, to slip through the bevel-wheels a^2 , which 90 connects such shaft with the worm-shaft, to compensate for various adjustments of the mandrel-head o' upon the column. The worm-shaft is shown with change-wheels n^2 at its right-hand end in Fig. 4, which may be used 95 to connect it with the usual stop mechanism to determine the arc through which the gear-blank q is rotated. The friction-driver t^3 (shown in Figs. 1 and 3) is the usual means of connecting the driving-shaft with the worm, 100 so that the connection may slip when the change-wheels n^2 are arrested by the stop mechanism, and the novel feature in this construction is the introduction of the change-wheels t^2 in the train which connects the driving-shaft with the worm n and which determines the speed at which the worm may rotate relative to the driving-shaft when the change-wheels n^2 are free or released in shifting the gear-blank. 110

115 It is obvious that the trains of gearing which are shown to connect the driving-shaft e' with the various mechanisms may be modified in construction without departing from the essential features of the invention, which consist, first, in the supporting of the driving-shaft in a line with the joint of the hinge-plate to maintain its connection with the cutter and the feeding mechanism of the cutter-head in their variously-adjusted positions. 120 Where the table c is adjustable upon the bed, the bearing of the driving-shaft necessarily varies in its distance from the dividing-worm n' , and an essential feature of the invention in such case consists, secondly, in the provision of a sliding connection, like the splined shaft t , between the driving-shaft 125

and the worm n . In a machine where the cutter-slide is elevated at an angle and provided with such driving mechanism it is desirable to furnish a connection between the cutter-slide and the mandrel which supports the blank, so as to hold the two firmly in a fixed relation during the cutting of such blank, as otherwise the cutter-slide would be supported only by the segments f . To thus connect the slide and mandrel, I attach an auxiliary bearing u' to the bearing o' , which supports the mandrel o adjustably upon the column b , and extend an arm u from such auxiliary bearing and connect the same with the end of the cutter-slide by a pivot-link w . The link is pivoted upon an ear x at the outer end of the cutter-slide and is slotted to fit a bolt w' upon the end of the arm u , and the bolt is tightened when the link and arm are properly adjusted. The link is thus adapted to assume any position and relation to the arm that is required in practice and to firmly connect the cutter-slide with the arm, and thus with the mandrel, through the agency of the bracket v . The arm u carries a bracket v to support the outer end of the mandrel, and as the mandrels used in such machines vary in length the bracket is made adjustable upon the arm, so as to be fitted to the outer end of the mandrel in the usual manner. The bearing u' is shown with a cap to clamp the arm u adjustably, and the arm may thus be slid backwardly in the bearing within the column b , as is indicated in Fig. 6. The bearing u' is adjustable vertically upon the column b with the bearing o' in the usual manner, and the parts are shown arranged in Fig. 5 to apply a cylindrical blank to the mandrel to cut spur-teeth upon the same. In such case the cutter-slide h is horizontal; but Fig. 6 shows the cutter-slide elevated thirty degrees by operating the segments f , and the ear x is thus brought quite close to the end of the arm u . The link w is shown inclined and the arm pushed backwardly in the bearing u' to bring the bolt w' of the arm in the slot of the link w . A short mandrel is shown in the bearing o' , and a blank q , with beveled face, is shown upon the mandrel and adjusted to be cut by the cutter c .

The various connections and adjustments described herein greatly increase the efficiency of the machine, and all coöperate to diminish the labor of the attendant and to cut the gears more perfectly.

Having thus set forth the nature of the invention, what is claimed herein is—

1. A gear-cutter having the horizontal bed a , the table c adjustable upon the bed, the hinge-plate d jointed upon the table and the cutter-slide h pivoted upon such hinge-plate, the bearing g attached to such table and supporting the driving-shaft e' in line with the joint of the hinge-plate, a horizontal bearing g^2 connected with the bearing g and a horizontal driving-shaft as the shaft t extended

through such bearing and connected by gearing with the shaft e' , whereby the motion of the driving-shaft can be imparted to the cutter when the hinge-plate is adjusted at various angles upon the table, substantially as herein set forth. 70

2. A gear-cutter having a table with a hinge-plate jointed thereon and supporting a cutter-slide with a cutter-head and feed-gearing for reciprocating the same, a bearing attached to the table with a driving-shaft in line with the joint of the hinge-plate, and a train of gearing connecting the driving-shaft with the feed-gearing and with the cutter-spindle, as 80 and for the purpose set forth.

3. A gear-cutter having gearing with change-wheels to control the shifting of the blank, a bed with table adjustable upon the bed, a hinge-plate jointed upon the table, with 85 a cutter-slide supported upon such hinge-plate and a cutter-head movable upon the slide carrying a cutter-spindle and cutter to cut the blank, a bearing fixed to the table and supporting a driving-shaft in line with the 90 joint of the hinge-plate, and separate trains of gearing connecting the driving-shaft respectively with the cutter-spindle and with the change-wheels to control the shifting of the blank. 95

4. A gear-cutter having gearing with change-wheels to control the shifting of the blank, a bed with table adjustable upon the bed, a hinge-plate jointed upon the table with cutter-slide supported upon such hinge-plate, 100 and a cutter-head movable upon the slide carrying a cutter-spindle and cutter to cut the blank, a screw with gearing to reciprocate the cutter-head, a bearing fixed to the table and supporting a driving-shaft in line with the 105 joint of the hinge-plate, and separate trains of gearing connecting the driving-shaft respectively with the cutter-spindle, the feed-screw of the cutter-head, and the change-wheels to control the shifting of the blank. 110

5. A gear-cutter having gearing with change-wheels to control the intermittent shifting of the blank, a bed a with table c adjustable upon the bed, the cutter-slide h pivoted upon the table and adjustable angularly, 115 the cutter-head i movable upon the slide and carrying the cutter-spindle j , the feed-screw k with gearing at the outer end of the cutter-slide to reciprocate the cutter-head, the bearing d' attached to the table and supporting the shaft l parallel with the side of the table, a train of gearing connecting such shaft with the change-wheels to control the intermittent shifting of the blank, and a separate train of gearing connecting the shaft with the feed-screw k , and provided with the universal joints l to compensate for the angular adjustment of the cutter-slide, substantially as set forth. 120

6. A gear-cutter having gearing with 130 change-wheels to control the shifting of the blank, the table c adjustable upon the bed b ,

- the cutter-slide *h* pivoted upon the table *c* and adjustable angularly, the cutter-head *i* movable upon the slide and carrying the cutter-spindle *j*, the feed-screw *k* with gearing at the outer end of the cutter-slide to reciprocate the cutter-head, the horizontal bearings *g* and *d'* attached to the table, with the driving-shaft *e'* supported in the bearing *g*, and the shaft *l* supported in the bearing *d'* and connected with the shaft *e'*, and having the universal joint *l'* connected with the feed-screw gearing, the bearings *g'* and *g''* connected with the bearing *g*, and the shaft *t* mounted in the bearing *g''* and connected with the shaft *e'*, the whole arranged and operated substantially as herein set forth.
7. A gear-cutter, having the bed *a* and column *b* with means to support and rotate the blank, the table *c* adjustable upon the bed, the hinge-plate *d* with joint *e* upon the table, the segments *f* with gearing to elevate the hinge-plate, the bearing *g* secured to the table in line with the joint *e* for carrying the driving-shaft, the cutter-slide and cutter-head supported upon the hinge-plate, and separate trains of gearing connecting the driving-shaft *e'* respectively with the change-wheels to control the shifting of the blank, and with the cutter, substantially as herein set forth.
8. A gear-cutter having the bed *a* with table *c* adjustable thereon, and provided with joint *e* and bearing *g* carrying the driving-shaft *e'* in line with the joint *e*, the hinge-plate *d* having the cutter-slide *h* adjustably pivoted thereon, the cutter-head *i* carrying cutter-spindle *j*, the feed-screw *k* with gearing at its forward end to reciprocate the cutter-head, and the shaft *l* having the bearing *d'* upon the hinge-plate, and the bearing *h'* upon the cutter-slide and provided with the universal joints as set forth, connections between the shaft *l* and the feed-screw gearing, and gearing connecting the same shaft with the cutter-spindle *j*, whereby the cutter-slide may be adjusted laterally and the hinge-plate adjusted vertically and the moving parts driven by connection with the shaft *e'*.
9. A gear-cutter adapted for cutting worm-gears and bevel-gears as set forth, and having the bed *a*, the adjustable table *c*, the hinge-plate *d*, the cutter-slide *h* and the cutter-head *i* carrying the spindle *j*, the bearing *g* fixed upon the table and carrying the driving-shaft *e'* in line with the joint of the hinge-plate, a train of gearing connecting the driving-shaft with the cutter-spindle, and change-wheels, as *m*, interposed in such train to vary the speed of the cutter-spindle, as and for the purpose set forth.
10. A gear-cutter having a worm-wheel, a worm and change-wheels to control the shifting of the blank, and provided with the bed *a*, the adjustable table *c*, the hinge-plate *d* jointed to the table, the cutter-slide *h* and the cutter-head *i* carrying the spindle *j*, the bearing *g* fixed upon the table and carrying the driving-shaft *e'* in line with the joint of the hinge-plate, a train of gearing connecting the driving-shaft with the worm, and change-wheels interposed between the driving-shaft and worm, to vary the speed of the worm in shifting the blank.

11. A gear-cutter having the bed *a* and column *b* with mandrel-bearing supporting worm-wheel and worm *n* as set forth, the table *c* adjustable upon the bed, the hinge-plate *d* with joint *e* upon the table and the cutter-head and slide supported upon the hinge-plate as set forth, the bearing *g* secured to the table in line with the joint *e* for carrying the driving-shaft *e'*, and a train of gearing connecting the driving-shaft with the worm and including the horizontal shaft *t* adapted to slip through one of the driving-wheels to compensate for the various adjustments of the table *c* upon the bed.

12. A gear-cutter having a horizontal bed supporting a cutter-slide with a cutter-head movable upon the same and feed-gearing for reciprocating the head, the gear-case *k'* upon the forward end of the slide containing the feed-gearing, a driving-shaft with connection to such gearing, the bevel-gears *s* mounted upon the cutter-head and connected with the cutter, and the shaft *m'* connected with the feed-gearing and extended through one of the bevel-gears *s*, to drive the cutter in the various positions of the cutter-head, substantially as herein set forth.

13. A gear-cutter having a worm-wheel, a worm and change-wheels to control the shifting of the blank, and provided with the bed *a*, the adjustable table *c*, the hinge-plate *d* jointed upon the table, the cutter-slide and cutter-head supported upon the hinge-plate, the bearing *g* fixed upon the table and carrying the driving-shaft *e'* in line with the joint of the hinge-plate, and a train of gearing connecting the said driving-shaft with the worm, such train embracing the bevel-gears *a'* and the splined shaft *t* extended through one of the said gears to rotate the worm in the different adjusted positions of the table *c*, substantially as herein set forth.

14. A gear-cutter having the bed *a* and column *b*, the mandrel-bearing adjustable thereon, and having an arm projected parallel with the bearing and a bracket adjustable upon the arm to support the end of the mandrel, the hinge-plate *d* with cutter-slide and cutter-head supported thereon, gearing to elevate the hinge-plate and an adjustable connection between the cutter-slide and the arm to hold the cutter firmly in relation to the blank.

15. A gear-cutter having the bed *a* and column *b*, the mandrel-bearing adjustable upon the column and provided with auxiliary bearing *u'* with arm *u* held adjustably therein, and the bracket adjustable upon the arm

to support the mandrel, the hinge-plate with cutter-slide and cutter-head supported thereon, gearing to elevate the hinge-plate, and the pivot-link *w* connecting the outer ends 5 of the cutter-slide and the arm adjustably, to hold the cutter firmly up to the blank when the cutter-slide is inclined.

In testimony whereof we have hereunto set

our hands in the presence of two subscribing witnesses.
